Patented May 2, 1922.

UNITED STATES PATENT OFFICE.

GUSTAF A. ANDERSON, OF BALTIMORE, MARYLAND, ASSIGNOR TO THE T. H. SYMINGTON COMPANY, OF NEW YORK, N. Y., A CORPORATION OF DELAWARE.

CAR TRUCK.

1,414,924.

Specification of Letters Patent. Patented May 2, 1922.

Application filed February 1, 1922. Serial No. 533,373.

To all whom it may concern:

Be it known that I, GUSTAF A. ANDERSON, a citizen of the United States, residing at Baltimore city, in the State of Maryland, 5 have invented certain new and useful Improvements in Car Trucks; and I do hereby declare the following to be a full, clear, and exact description of the invention, such as will enable others skilled in the art to which 10 it appertains to make and use the same.

My invention relates to car trucks for railway cars and particularly to a form of flexible truck having side frame members whose longitudinal and other displacement 15 movements from normal square position are yieldingly restrained and cushioned, said side frame members being restored to normal position upon cessation of the forces producing the displacement movement. Generally stated, the present invention consists 20 in providing a plurality of yieldable devices located within the truck and interposed between the side frame members and connecting means therefor, said devices acting in 25 unison to resist displacement movement of the side frames and to restore the same to normal position.

The principal object of my invention is to provide means associated with the spring 30 plank and side frame members for effectively receiving and distributing the displacement movements and shocks among several yieldable devices, all of which become energized simultaneously for any angular deflection of 35 the said truck parts from normal position, the energized yieldable devices serving to restore the parts to normal position upon cessation of the forces producing displacements.

40 The principal feature of the invention by which this object is accomplished consists in providing spaced spring devices about the pivotal connection of the side frame members and connecting means therefor, said 45 spring devices producing parallel forces simultaneously actuated in opposite directions about the said pivotal connection for resisting displacement movement of the side frames and restoring the same to normal 50 position. The movement of the parallel forces, both of which operate at one and the same time and in opposite directions for any displacement of the side frame members

from normal position, constitutes a "couple" 55 in which all strain incident to such displacement upon the pivotal connections between the side frames and the spring plank is reduced to a minimum.

A further feature of the invention is to produce spaced spring devices, each of which 60 includes a spring of relatively reduced capacity as compared with the size of a spring operating independently of a couple, both of said springs being based upon the same value of deflecting movement between the 65 spring plank and side frame.

Other objects and features of my invention will hereinafter appear.

In the drawings illustrating an embodiment of my invention, the scope whereof is 70 pointed out in the claims:

Figure 1 is a plan view partly in section of a car truck, with my improved squaring mechanism applied thereto, the several parts being shown in the angular relation they assume when passing around a curve. 75

Figure 2 is a detail transverse sectional view on the line 2—2 of Figure 1.

Figure 3 is a detail horizontal sectional view through a portion of one side frame 80 and associated yieldable couple.

In the drawings, 1 indicates transversely spaced side frame members which are relatively movable longitudinally of the truck. Each side frame is provided at its opposite 85 ends with the usual journal boxes receiving the journal ends of the axles 2 upon which the wheels 3 of the truck are mounted.

The side frames 1 are movably connected across the truck by a suitable connecting 90 means 4 which may conveniently constitute a truck spring plank. When constructed as a spring plank the opposite ends of the cross connecting means 4 may extend into the respective bolster openings 5 of the side frames 95 and there be pivotally connected to said frames 1. The pivotal connection of the spring plank with the side frames may be effected by providing each side frame centrally of its bolster opening with an upwardly projecting pivot boss 6 which extends into a corresponding opening 7 of the spring plank. Sufficient clearance is provided between the sides of the spring plank 4 and the neighboring faces of the columns 8 of 100 the side frames to allow the spring plank to 105

turn freely through an angle corresponding to the maximum relative longitudinal displacement from normal which it is desired that the side frames 1 shall have. As is 5 usual in flexible trucks, the truck bolster also has sufficient clearance from the truck columns 8 to permit it to angle horizontally without binding upon said columns when the side frames 1 are disposed longitudinally 10 to their full extent from square relation.

The yieldable means includes spaced spring devices 9, each group of spaced spring devices constituting a "couple." I prefer to provide two couples or groups of spring devices, there being a couple arranged adjacent each side frame and interposed therebetween and the spring plank 4. The pivotal means movably connecting the spring plank and side frame members permits of 15 the use of but a single couple, the displacement of either or both of the side frames serving to actuate the parallel forces of the couple in first resisting said displacement movement and consequently restoring said 20 side frames to normal position.

Two spring devices are included in each couple, each spring device being arranged upon opposite sides of a line passing through the pivotal connections of the spring plank 30 and side frame members. Springs 10-11 constitute the yieldable means I prefer to employ in each couple although other yieldable mediums may be used. The springs are arranged in pockets 12 formed in a housing secured by means of rivets 13 to the spring plank. The pockets are oppositely arranged and may be formed integrally with or may be joined by a web or plate section 14. Abutment walls 15 and 16 are 35 provided at opposite ends of the housing and between said walls and the respective opposite ends of the springs 10-11 are arranged flanged followers 17 and 18.

The followers 17 and 18 are loosely mounted upon a rod 19 provided at one end with a head 20 adapted to bear against the follower 18 and having its opposite end arranged to pass through the side frame member and threaded to receive a nut 21. The nut 21 45 bears against the outer face of the side frame member and together with the head 20 on said rod, serves to connect the side frame member and spring plank whereby movement of one or the other of said truck parts 50 will be transmitted through the yieldable springs in either resisting displacement movement or effecting the restoration of the truck parts to normal position.

The springs 10-11 of each spring device 55 are simultaneously energized from the opposite ends thereof, any angular deflection of the side frame member and spring plank with respect to each other, causing the followers 17 or 18 of the respective spring devices of each couple to compress the spring

from its respective ends. Each end of each spring is yieldingly associated with or connected to the side frame members, the follower 18 and rod 19 connecting the inner end of the spring, and the follower 17, and more 70 especially the projecting end 22 thereof, serving to operably connect the outer end of the spring with said side frame by contact therewith.

A truck constructed in accordance with 75 my present invention will rapidly respond to the restoration forces upon cessation of the forces acting to produce displacement movement. The simultaneous and substantially uniform energization of the spring devices when resisting displacement movement, produces corresponding and simultaneously acting restoration forces of a uniform nature which, when acting as they do in "couples," causes an effective distribution 80 of said forces with practically little, if any, wear on the pivotal connections between the side frame members and spring plank. The springs used in the yieldable device may, as the result of their action in unison, be correspondingly less in size and capacity as 85 compared with springs, the functions of which are only called into operation for certain displacement movements.

It will be obvious that a railway track roadbed in which the curves, switch points, or other irregularities produce angular deflection of the side frame members with respect to the spring plank, in substantially the same manner, would tend to overload or 90 overwork certain of the springs where their operation is independent. In the present case, however, all of the springs 10-11 are operated at one and the same time for any angular deflection and the work of said 95 springs, as a result, is uniformly distributed.

Upon longitudinal or other displacement of the side frames from normal square position the spring plank assumes an angular position with respect to said side frames, as 100 shown in Figure 1. The movement incident to this displacement shock is about the pivotal connections of the spring plank and side frame members and each spring device 105 of each couple acts to resist the movement. The springs of each couple are therefore energized from opposite ends, it being apparent that the nose 22 of the follower 17 110 presses against the side frame and upon one side of the pivoted connection causing a compression of one of the springs 11 between 115 said follower 17 and the opposite follower 18, both of which followers are moved toward each other by virtue of the angular position assumed by the spring plank. The 120 adjacent spring 10 of the couple upon the opposite side of the pivotal connection is also compressed between the respective followers 17 and 18, the follower 18 being moved by the head 20 of the rod, said fol- 125 130

lower moving away from the end wall of the spring housing or pocket. In this case the angular deflection of the spring plank also serves to move the follower 17 out of contact with the side frame and cause it to assist in the compression of the spring. The respective springs of each couple are, as a result of the angular movement of the spring plank compressed from opposite ends, but the 10 acting forces of said springs as the result of said compression are in parallel and opposite directions, so as to act as a couple and swing the side frame members about their pivotal connections when restoring them to 15 normal position.

The springs 11 may be assembled within the housing under initial tension, and in the preferred embodiment of the invention the followers 17 are normally in contact with the 20 inner face of the side frame members and the follower 18 is operably held against said springs.

In practice I prefer to notch the abutment walls 15 and 16 of each housing to provide 25 ready means for effecting the insertion of the several parts from the top of the housing, the spring plank projecting over far enough to insure the retaining of the springs and associated parts in proper position.

30 I claim:—

1. In a car truck, the combination with 35 movable side frame members, of means connecting said side frame members, and oppositely disposed yieldable means for resisting displacement movement of the side frame members from normal position, said yieldable means including spaced spring devices interposed between the side frame members and said connecting means and 40 adapted to be simultaneously energized when resisting displacement movement.

2. In a car truck, the combination with 45 movable side frame members, of means connecting said side frame members, and a plurality of devices for yieldingly resisting displacement movement of the side frame members from normal position, said devices being simultaneously energized by said displacement movement for restoring the side 50 frame members to normal position upon cessation of the forces producing the displacement movement.

3. In a car truck, the combination with 55 independently movable side frame members, of means connecting said side frame members, and a plurality of yieldable devices carried by said connecting means and arranged adjacent each side frame member for resisting displacement of said side frame members 60 from normal position, said yieldable devices being simultaneously energized by the displacement movement for restoring the side frame members to normal position upon cessation of the forces producing the displacement movement.

4. In a car truck, the combination with 70 longitudinally movable side frame members, of means pivotally connecting said side frame members, and yieldable means located upon each side of the pivotal connections of the side frame members and connecting means, said yieldable means being adapted to simultaneously resist displacement movement of the side frame members and arranged to be simultaneously energized for 75 restoring the side frame members to normal position.

5. In a car truck the combination with 80 movable side frame members, of means including a spring plank connecting said side frame members, and yieldable means for cushioning the displacement movement of the side frame members from normal position, said yieldable means including spaced spring devices adapted to be energized at one 85 and the same time for any direction of angular displacement between the spring plank and side frame members.

6. In a car truck, the combination with 90 longitudinal side frame members, of transverse means pivotally connecting said side frame members for permitting displacement movement of the side frame members from normal position, and yieldable means arranged transversely of the truck upon each 95 side of a line passing through said pivotal connecting means, said yieldable means being adapted to be energized for any direction of angular displacement between said transverse connecting means and side frame 100 members.

7. In a car truck, the combination with 105 side frame members, of means movably connecting said side frame members for permitting displacement movement thereof from normal position, and means for restoring 110 said side frame members to normal position, said means including spring devices interposed between the side frame members and said connecting means and adapted to operate simultaneously.

8. In a car truck, the combination with 115 side frame members, of means movably connecting said side frame members, and yieldable means including a spring having each end thereof connected with the side frame member for resisting displacement movement in any angular direction, said spring becoming energized by the displacement movement and serving to restore the side 120 frame members to normal position.

9. In a car truck, the combination with 125 side frame members, of transversely extending means for pivotally connecting said side frame members, and yieldable means including a spring located outside of a line passing through the said pivotal connection of the side frame members and having each end thereof interconnected with at least one of the side frame members for resisting dis- 130

placement movement in any angular direction, said spring serving to restore the side frame members to normal position.

10. In a car truck, the combination with 5 side frame members, of transversely extending means for pivotally connecting said side frame members, and yieldable means including a horizontally disposed spring mounted on the said transversely extending 10 connecting means and having each end thereof connected with at least one of the side frame members for cushioning displacement movement in any angular direction, said spring also serving to restore the side frame 15 members to normal position.

11. In a car truck the combination with independently movable side frame members, of means connecting said side frame members, and yieldable means for resisting displacement 20 movement of said side frame members from normal position, said yieldable means including a spring, followers provided at each end of said spring and means including the side frame member for actuating 25 one or the other of said followers for energizing the spring.

12. In a car truck, the combination with independently movable side frame members, of means connecting said side frame members, and yieldable means for resisting displacement movement of said side frame members from normal position, said yieldable 30 means including a spring, a pocket formed with opposite abutment walls, and followers 35 interposed between said abutment walls and the respective opposite ends of said spring, each of said followers being operably connected with the side frame member.

13. In a car truck, the combination with 40 independently movable side frame members, of means connecting said side frame members, and yieldable means for resisting displacement movement of said side frame members from normal position, said 45 yieldable means including a spring and housing therefor, followers arranged at the respective ends of said spring, one of said followers engaging the side frame members and a rod connecting the other of said 50 followers to said side frame member.

14. In a car truck, the combination with movable side frame members, of means connecting said side frame members, and yieldable means for resisting displacement movement of the side frame members from normal position, said yieldable means including a plurality of spring devices energized 55 by said displacement movement and acting

as a couple for restoring the side frame members and said connecting means to normal position.

15. In a car truck, the combination with movable side frame members, of means connecting said side frame members, and yieldable means interposed between said connecting means and side frame members, said yieldable means acting as a couple in cushioning the displacement movement of the side frame member from normal position and similarly acting in restoring the side frame members and connecting means to normal position.

16. In a car truck, the combination with movable side frame members, of means connecting said side frame members, and yieldable means interposed between said connecting means and side frame members, said yieldable means being energized by the displacement movement of said side frame members for action as a couple in restoring the said truck parts to normal position.

17. In a car truck, the combination with movable side frame members, of means pivotally connecting said side frame members together, and means for maintaining said side frame members and connecting means in normal square position, said means including a pair of spring devices acting about the aforesaid pivotal connection as a couple.

18. In a car truck, the combination with movable side frame members, of means pivotally connecting said side frame members together, and means including actuating devices operating as a couple for maintaining said side frame members and connecting means in normal square position.

19. In a car truck, the combination with movable side frame members, of means pivotally connecting said side frame members together, and truck squaring means interposed between the side frame members and pivotal connecting means, said means involving parallel forces simultaneously actuated in opposite directions about said 105 pivotal connecting means.

20. In a car truck, the combination with movable side frame members, of means pivotally connecting said side frame members together, and means involving devices 110 operable in parallel about the said pivotal connecting means for maintaining the side frame members in normal position.

In testimony whereof I affix my signature.

GUSTAF A. ANDERSON.
